UNITED STATES PATENT OFFICE

2,547,697

ADJUSTABLE FESTOON

Conrad Gallo, Brooklyn, N. Y.

Application July 1, 1949, Serial No. 102,579

1 Claim. (Cl. 160—330)

1 This invention relates to new and useful improvements in decorative draperies, as for windows and the like, and, more particularly, the aim is to provide a novel and valuable drape characterized by a formation such that there are a plurality of separate and specially correlated panel and valance or festoon members permanently interconnected in an improved manner.

An object of the invention is to provide a uniquely attractive drapery ensemble, yet one which may be inexpensively made, securely but simply interconnected as to its panel and festoon elements, and at the same time adapted to be arranged, when in applied position, as over a rod or other suitable support extended horizontally adjacent to the top limit of a window, doorway or the like, in such a way that the connections between said panel and festoon elements are completely hidden; with the result that the drapery ensemble, made of separate pieces of textile material or the like and all of outlines permitting the use of cutting patterns arrangement for the minimization of waste material to the utmost, apparently is a de luxe single sheet structure variously folded and arranged after having been cut solely for purposes of attaining beautiful lines when hung, without regard to possible extra cost ensuing from expensive material wastage.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a front elevational view, showing one now favored embodiment of the drapery ensemble of the invention, as hung from a curtain rod; that is, showing said ensemble as it would be seen from the inside of the room, and in one of the many possible adjustments thereof to adapt the ensemble to the width of the particular opening in regard to which it is hung and also to obtain at the festoon element a then particularly desired array of downwardly arched corrugation-suggesting undulations.

Fig. 2 is a somewhat enlarged detail view, this fragmentarily showing one side of said ensemble, looking toward the rear or hidden side of the latter before the ensemble is applied to the curtain rod, that is, with the parts arranged as in Fig. 3.

Fig. 3 is a vertical section, taken on the line 3—3 of Fig. 2.

Fig. 4 is a vertical section drawn to the same scale as Figs. 2 and 3, but taken on the line 4—4 of Fig. 1.

Fig. 5 is a front elevational view, showing said

ensemble as spread substantially flat before being reversed and then hung from the curtain rod.

Fig. 6 is a view similar to Fig. 1, showing a modification.

Fig. 7 is a view similar to Fig. 5, showing said modification.

Referring to the drawings more in detail, and first to Figs. 1-5, the new drapery ensemble here illustrated is shown as comprising a central valance or festoon element 10 and a pair of like but reversely facing end panel elements 11, 11.

The patterns used for the cutting of each of said panel elements 11 may be such that the opposite sides of a panel are parallel, one end thereof is straight and substantially at right angles to said sides, and the opposite end thereof rectilinearly oblique, as to have substantially a 45° inclination. Then, when the panels 11 are ruffled as shown in Figs. 1, 2 and 5, a final aesthetically pleasing drape results, of the kind shown in the two views last-named. Such rufflings may be tacked down as by application of the stitchings 12 (Fig. 2).

The festoon element 10 desirably has a smoothly curvilinearly extended edge for defining, as illustrated, the bottom and side margins of said element. As here shown, the top margin of said element 10 is cut so that, with the drapery ensemble completed by the permanent joining of the two panel elements with the festoon element 10, and with the ensemble spread flat as in Fig. 5, said top margin of the element 10 has main terminal portions which downwardly outwardly slope, as clearly seen in the last-named view.

35 A tunnel 14 extends along the entire width of the drapery ensemble as completed according to the showing of Fig. 5, and said tunnel is closed in along its bottom in any suitable way, as by the line of stitching marked 15 in Fig. 2. This stitching 15 is also seen in Figs. 3 and 4. The tunnel 14 is shown as established by a separate rectangular strip of material, folded longitudinally on itself and opposite the bight of its said folding secured to the elements 10 and 11, 11 by the stitching 15.

It is particularly to be noted that with the stitchings 12 and 15 applied as explained, that is, with the top rufflings of the panel elements 11, 11 located at what is to be the back or hidden side of the drapery ensemble, as perhaps best shown in Fig. 3 as taken along with Fig. 2, and then when, before passing the curtain rod 16 through the tunnel 14, the latter is forced to dependency as shown in Fig. 4, the ensemble becomes draped as in the last-named view, with all the stitchings fully hidden.

With the tunnel 14 adequately exceeding in length the length of the curtain rod 16, rufflings of said tunnel will be set up along the tunnel, as

shown in Fig. 1, with the festoon effect also clearly shown in Fig. 1.

Referring to the modification illustrated in Figs. 6 and 7, wherein the parts to which are applied reference numerals with primes, added correspond, respectively, to the parts to which have been applied the same reference numerals without primes, the chief difference here involved is that two like festoon elements 10' are included in the ensemble, with these elements arranged so as to overlap somewhat, not only the adjacent panel element 11' as in Figs. 1-5, but each other, at the central portion of the ensemble, as at 11.

Thereby, such an effect as that shown in Fig. 6 may be obtained. In this connection, it will be noted that, as shown, the portion of the tunnel 14' overlying the two festoon elements 10', 10' is preferably of M-shaped longitudinal extension, while there are also present two end extensions 14^a, 14^a of said tunnel; each of these last substantially horizontally aligned and with each extending along part of the width of the ruffled top of a different one of the panel elements 11', 11'.

It is to be understood that the two sides of panels 11 may be of different color or design and be removably secured in position on the central valance or festoon 10 by means of snap fasteners, hooks and eyes, etc., so that either sides of the panels 11 and festoon 10 may be used.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A drapery ensemble, comprising a central festoon piece having upwardly and inwardly converged top edges which meet at the center of said festoon forming a top edge in the shape of a flattened obtuse angle, a tunnel formed of superimposed plies of material doubled upon themselves along their longitudinal center to have adjacent longitudinal edges facing upward, said tunnel being longer than the top edge of said festoon piece and positioned in front of said festoon piece with its ends projected equally to either side of said festoon piece and with the tops of its longitudinal edges flush with the top edge of said festoon piece, depending end panels at the sides of said festoon piece with their top edges located behind the projecting ends of said tunnel, said end panels having their top edges flush with the tops of the longitudinal edges of the projecting ends of said tunnel and with their inner side edge portions located behind the sides of said festoon piece, and stitches securing the upwardly facing longitudinal edges of said tunnel to the top edges of said festoon piece and said end panels, so arranged and constructed that when a curtain rod is engaged through said tunnel said festoon piece will be draped behind the curtain rod and said end pieces can have their free ends folded over the top of the curtain rod to depend freely in front of the curtain rod.
